UNITED STATES PATENT OFFICE.

VINCENT A. MENUEZ, OF MEMPHIS, TENNESSEE.

EXTENSION-LAMP.

SPECIFICATION forming part of Letters Patent No. 761,845, dated June 7, 1904.

Application filed September 22, 1902. Serial No. 124,403. (No model.)

To all whom it may concern:

Be it known that I, VINCENT A. MENUEZ, a citizen of the United States, residing at Memphis, Shelby county, State of Tennessee, have 5 invented certain new and useful Improvements in Extension-Lamps, of which the following is a specification.

My invention relates in general to improvements in extension-lamps, and especially to 10 that class in which oil or gasolene is stored in a reservoir, from which it is forced by compressed air through suitable distributing-pipes to the lamps.

The objects of my invention are to improve 15 the lamp in general and in detail to provide ready access to same for filling, cleaning, and lighting and at the same time to reduce the cost. I accomplish these objects, first, by providing a simple, cheap, and effective extension-tube to permit access to the lamp; second, by providing means for filling the reservoir with compressed air from beneath, and, 20 third, by providing a special form of reservoir which is shaped to allow the extension-case to come compactly against and partially into it, all of which will be more fully herein-after set forth in the drawings, specification, and claims.

In the drawings, Figure 1 is a sectional elevation on the center line, showing my lamp, reservoir, and extension complete. Fig. 2 is a sectional plan on the line II II of Fig. 1 looking in the direction of the arrow; and Fig. 3 is a sectional elevation on the line III III of Fig. 2 looking in the direction of the arrow, the two showing in detail the construction of the support for the raising-cord. Fig. 4 is a sectional elevation showing a coupling which is used when the supporting-tube is to be extended for extra high ceilings. Fig. 5 is a sectional elevation showing the frame which supports the spring-raising drum in section, taken on the center line and the drum in elevation. Fig. 6 is a side elevation and section 45 on the line VI VI of Fig. 5. Fig. 7 is a detail view of the center portion of the side frame 8.

Referring now to the drawings, in which the

same numeral refers to the same or like parts in all the views, 1 is the oil-reservoir, from 50 which tubes 2 2 lead off at either side to the burners. (Not shown.)

3 is a tube open at both ends, which passes centrally through the reservoir 1 and is brazed air-tight to it at both its upper and lower ends. 55 At the upper end this tube extends beyond the reservoir and is fastened preferably by a screwed joint into the sleeve or cuff 4, which forms the lower end of a frame 5, in which the spring-raising drum 6 is journaled. This 60 frame consists of two similar and parallel sides 7 8, oppositely disposed, connected at the bottom by the cuff 4 and at the top by a cuff 9, into which a tube 10, designated the "sliding" tube, is screwed to guide the frame when 65 it is being lowered or raised.

11 is an ornamental casing which surrounds the drum 6 and frame 5 and which rests against the reservoir 1 when same is in the raised position. 70

The drum 6 is carried on a shaft 12, mounted in the frame 5 and held from rotating by a pin 13, which bears against lugs 14 and 15 on the side 7 of the frame 5.

The shaft 11 is formed, preferably, of a 75 piece of tubing having one side open to form a slot in which the ends 16 of the raising-drum 17 is inserted.

18 is a handle by which the tension of the spring may be regulated. 80

19 is a cord, which is fastened to and wound around the drum 6 and which when the lamp is lowered is unwound, thereby winding up the spring 17. 20 represents hooks fastened to the ends of the cord 19, which engage in openings 85 21 in the sides of the drum. From the drum this cord extends upward over a roller 22, journaled in the cuff 9 and within the tube 23. This tube, designated the "fixed" tube, is supported by a hanger-loop 24 and serves as a 90 guide for the sliding tube 10. The cord 19 is upheld in the tube 23 by a cord-support 25, which rests on an internal bead or shoulder 26 in the said tube. This support being internal leaves the outside of the tube smooth, 95 so that the outer tube will slide freely on it,

and since it has no connection with the end of the tube allows same to be lengthened for a high ceiling without disturbing the cord-support.

5 In Fig. 4 I show a coupling 27, fastened to the upper end of the tube 25, and an extra length of tubing 28, extending upward therefrom. If the hanger-loop 24 be made with a female thread instead of male thread, as shown, 10 this extension may be fitted without trouble to the end of the tube 23 and the hanger-loop 24 be screwed on the end of the extra tube, as it now is on the tube 23.

The weight of the lamp is balanced by a 15 coil-spring 17, (before mentioned,) which spring is contained within the drum 6 and is not shown in detail, since it is of ordinary type. The sides 29 30 of the drum 6 are provided with peripheral notches 31, which are 20 engaged by detents 32, carried by a yoke 33. These detents are slidably mounted between guides 34, which are integral with the side frames 7 8. An extension or shank 35 of the yoke 33 extends downward therefrom into 25 the tube 3 and has a rod 36 fastened into it, which rod extends through the entire length of the said tube 3 and projects beyond it, being preferably supported at its lower end by a sliding bearing in the ornamental scroll 37, 30 which projects beneath the reservoir 1. The detents 32 are held in engagement with the notches 31 of the drum 6 by a compression-spring 38 in the lower end of the tube 3. This 35 spring is supported by a sleeve or bushing 39, screwed into the lower end of the said tube, and bears against a collar 40, fastened on the rod 36.

41 is a hand-grip fastened on the rod 36, which is grasped to depress the rod 36, and 40 thereby disengage the detents 32 from the notches 31 to allow the lamp to be moved up or down.

42 is an air-tube extending from an automatic air-inlet valve 43 in the lower side of 45 the reservoir 1 to the upper portion of the said reservoir above the usual level of the gasoline. This tube is so placed in order that air may be pumped into the reservoir from a pump below same and for convenience in attaching 50 the pump-pipe. 44 is a valve for filling the reservoir with gasoline. The upper portion of the reservoir may be depressed, as shown at 45, in order to make the extension-tube longer and the fixture more compact. In this case, as 55 shown, the case 11 fits down on it, making an ornamental figure for the entire lamp design.

In use the lamp is lowered by grasping the handle 41 and disengaging the detent 32 from the notches in the drum and pulling the lamp 60 downward, the cord 19 unwinding from the drum as the lamp lowers and the tubes 10 and 23 guiding the motion until the handle 41 is released and the drum held from further rotation. When the detents are again removed 65 from the notches in the drum, they allow same

to turn and wind up the cord 19, thus raising the lamp.

In filling the reservoir with air the air-pump tube (not shown) is attached in the usual manner to the valve 43 below the reservoir, and 70 air is pumped in after the proper amount of oil has been put in the reservoir.

Having now fully described my invention, what I claim, and desire to secure by Letters Patent of the United States, is—

75

1. In an extension for a lamp, the combination with a frame, a drum journaled in said frame, a cord wound on said drum, a sliding tube fastened to the upper end of said frame and a fixed tube within said sliding tube, of 80 an internal bead in said fixed tube and a cord-support resting on said bead, substantially as shown and described.

2. In an extension-lamp, the combination with a fluid-reservoir, a central tube through 85 said reservoir, a frame fastened to the upper end of said tube, a spring-actuated drum, a detent for said drum, a sliding tube extending upward from said frame, a fixed tube within said sliding tube and a flexible connector 90 from said fixed tube to said drum, of a filling-tube extending upward from the bottom of said reservoir above the line of the liquid in same, substantially as shown and described.

3. In a lamp extension, the combination 95 with a fluid-reservoir, a central tube through said reservoir, a frame fastened to the upper end of said tube, a spring-actuated drum journaled in said frame, notches in the periphery of the sides of said drum, and a detent, of a 100 rod extending downward from said detent through said central tube, a collar on said rod, a compression-spring bearing against said collar, a bushing in said central tube supporting said spring, a finger-grip, a sliding tube extending upward from said frame, a fixed tube within said sliding tube, an internal bead in said fixed tube, a flexible connector wound on said drum, and a support for said connector resting on said bead, substantially as and for 110 the purposes set forth.

4. In a lamp extension, the combination with a fluid-reservoir having the upper portion depressed, a centrally-disposed tube through 115 said reservoir, a frame fastened to the upper end of said tube, and a spring-actuated drum journaled in said frame, of a sliding tube extending upward from said frame, a fixed tube within said sliding tube, an internal bead in said fixed tube, a flexible connector wound on 120 said drum and a support for said connector resting on said bead, substantially as and for the purposes set forth.

5. In a lamp extension, the combination with a fluid-reservoir, having a depression in 125 the upper portion, a centrally-disposed tube through said reservoir, a frame fastened to the upper end of said tube, a spring-actuated drum journaled in said frame, notches in the periphery of the sides of said drum and a de- 130

tent engaging said notches, of a sliding tube extending upward from said frame, a fixed tube within said sliding tube, an internal bead in said fixed tube, a flexible connector wound on said drum and a support for said connector resting on said bead, substantially as and for the purposes set forth.

In testimony whereof I have signed my name to this specification in the presence of two subscribing witnesses.

VINCENT A. MENUZ.
